UNITED STATES PATENT OFFICE.

JOSEPH A. ARTHUR, OF BRIDGEPORT, CONNECTICUT.

PROPELLER FOR NAVIGABLE VESSELS.

No. 833,364.

Specification of Letters Patent.

Patented Oct. 16, 1906.

Application filed February 15, 1905. Serial No. 245,720.

To all whom it may concern:

Be it known that I, JOSEPH A. ARTHUR, a citizen of the United States, residing at Bridgeport, in the county of Fairfield and State of Connecticut, have invented certain new and useful Improvements in Propellers for Navigable Vessels; and I do hereby declare the following to be a full, clear, and exact description of the invention, such as will enable others skilled in the art to which it appertains to make and use the same.

15 My invention relates to propellers or screws for navigable vessels operated by steam or other power; and it consists in the use of a tapering shell by which "churning" of the water is prevented and in the combination therewith of reversible blades or flukes of a peculiar construction and arrangement.

It is well known that with screws of ordinary construction driven at a high speed the water which receives the impact of the blades circulates and tends to return toward the center, so that the blades tend to strike the same water as it circulates, called "churning," and much power is wasted. I have overcome this by the use of a tapering shell rearwardly extending from the propeller and by the use therewith of blades made concave on such a curve as to direct the water to a center behind the point of the shell. The water cannot return to the center on account of the shell, and if it tends to return on the sides thereof it strikes directly against the water coming from the blades.

35 The blades are journaled on suitable arbors or rock-shafts in the front portion of the shell, so that they rotate with the shell always in one direction, diminishing the strain on the engine and connections and may be
40 swung by suitable means to reverse them and drive the vessel in the opposite direction or to change their inclination with reference to the water more or less, ("feathering") so that
45 their inclination and the speed of the vessel may be easily and properly proportioned to their speed of rotation.

As here shown, the propeller is provided with two blades whose respective rock-shafts are arranged to roll on each other, permitting an easy swing and reversal.

I have provided a liquid thrust-bearing which is adapted to be used with the other parts of my invention.

55 My invention will be understood by reference to the drawings herewith, in which the

reference-numerals of the specification indicate the corresponding parts in all the figures.

Figure I is a side elevation showing the various parts of my invention, with portions broken away and portions shown in section. 60 Fig. II is an enlarged longitudinal section of the tapering shell and means for swinging the blades. Fig. III is a portion of Fig. II, showing a simple modification in the form and arrangement of the parts. Fig. IV is a plan of 65 a desirable form of blade. Fig. V is a cross-section of the blade on line V of Fig. IV. Fig. VI is a longitudinal section of the blade on line VI of Fig. IV. Fig. VII is an enlarged section of the thrust-bearing. 70

In the drawings, 1 indicates the stern of the boat provided on each side with the hub-pieces 2 tapering toward the front to part the water and prevent drag.

3 is the shaft, supported in ball-bearings or 75 other suitable bearings 4 4 and connected by any suitable means to the shell 6, carrying the blades 7. As here shown, this connection is a universal joint, permitting some freedom of movement between the parts to avoid 80 strain and a change in inclination of the shell, if desired, to steer the boat.

The shaft is provided with fork 10, in which is journaled ball 11, fitting socket 12 in front portion 13 of the shell, journaled on the ball. 85 The shell is rearwardly elongated, with sides preferably slightly convex the better to shed the water and avoid drag. This front portion 13 of the shell is preferably of spherical construction, fitting a socket in the stern of 90 the vessel, and by this means and by the ball 11, fitting socket 12, the propeller is firmly secured and maintained in position and easy adjustment is permitted. Also by this connection the shaft is entirely inclosed and the 95 drag of the water and engagement with grass, floating objects, &c., is avoided. This shell is adapted by its form to receive in its forward end in suitable bearings the parallel rock-shafts 14 14, arranged in contact and 100 each carrying one of the blades 7, which are

each carrying one of the blades 7, which are oppositely and reversely arranged, so as to coöperate when rotating. To each rock-shaft is connected one or more lever-arms 16, each connected by a link 17 to opposite ends 105 of cross-head 18, which is operated in any suitable way, as by sliding shifting-bar 20 to swing or reverse the blades. The lever-arms may be arranged as shown in Fig. III where the hub is sufficiently large; but for most purposes

poses I prefer the arrangement of arms shown in Fig. II, where each curves around the opposite rock-shaft, giving a greater leverage in a smaller shell. In either arrangement each 5 rock-shaft affords a roller-bearing for the other, so that they roll or turn easily in opposite directions, and a long bearing and firm support is thus afforded for each blade.

As shown in Fig. IV, the blades are preferably formed with the greater portion behind the blade-axis x , which permits easy reversing without strain or jerk on the shaft or engine. Their front or cutting edges y are also preferably inclined or curved back 10 from the shell outwardly, which tends to clear the blade of objects in the water, such as grass, ice, &c. As the blades always rotate in the same direction they may be made concave on their front faces and desirably with 15 an increased "pitch," so called, as the curve of the blade increases from the front edge to the back, and the front portion of the blade therefore meets the water at a finer angle, said angle (or curve) of meeting the water 20 gradually and uniformly increasing toward the back, Fig. VI. From this increased pitch, the blade takes the water gradually with less strain on the shaft, engine, &c., and when the blade is partially out of water or on a 25 dead-center, as in reversing, it opposes some 30 resistance and prevents the engine from running away. This increased pitch is combined in the blade with the natural screw and has the effect to increase the speed and 35 the power of the propeller, as it holds the water better. To swing the rock shafts and blades, I connect to the shifting-bar 20 a connecting-arm 25, pivotally supported on shoe 26 and guided in guide-slot of bracket 40 27. The lower end 29 of said arm may be forked and arranged in groove between shoulders 30 on shifting-bar. Said arm is operated to swing the blades by a conveniently-arranged operating-lever 35, sliding in bearings 34 and operated by hand-lever 36, provided with a suitable latch 37 to engage with notches on the shoe or elsewhere and lock the parts in position. Buffer-springs 38 45 may be arranged between the hand-lever and shoulders on operating-lever. The shoe 50 may be pivotally supported at 41 and on guide-bolt 42, so that it may be swung by tiller-rope or other means, together with the shell and blades, to operate as a rudder. To 55 engage with guide-bolt 42, the shoe is slotted at 44, permitting longitudinal adjustment of its upper arm slightly to raise or lower the propeller—that is, to incline it up or down to trim the vessel.

60 I do not wish to limit myself to the arrangement of parts shown, for that may be varied. Particularly the means for swinging the blades is not limited to operate from the rear and above, but may be otherwise arranged according to circumstances. Evi-

dently the shoe and external connecting arm would not be desirable for shallow waters in which grass, weeds, &c., were found.

It will be understood that the blades must be locked in adjusted position, and in that 70 connection the buffer-springs or equivalent buffer resistance is important to permit a certain resiliency to the blades and to take up lost motion, whereby strain on the engine and other parts will be avoided. Like the 75 increased pitch of the blades it opposes a certain resistance and saves strain when the engine tends to run away.

As is well known, thrust-bearings are 80 heavy and expensive, it being necessary to use many in large vessels to take up the great thrust of the shaft. I have devised a thrust-bearing which may be used in connection with my peculiar shell and other mechanism to take up the thrust by liquid pressure. 85 This is simple and economical to construct and lubricates some of the bearings.

On the shaft at any suitable point within the boat is fixed the piston 50, fitting within a case of any desirable construction, as of two 90 corresponding circular halves 51 51, fixed to any suitable part of the boat. The parts are so proportioned that at each end between the piston and its case there are left spaces 43 44 to be filled by water or other liquid 95 (oil is desirable) from the tank 56, within which is maintained a sufficient air-pressure, as of several hundred pounds, to force the liquid into said spaces through the tubes, 58 58 being check-valves to prevent backflow 10 into the tank. Connected to the shaft, as by cross-heads 60 60, are the valves 61 61 to shut off the flow of water through the respective pipes, so that when each space is alternately diminished its corresponding 10 pipe is closed; but when the space is increased the pipe is opened and a flow of water is permitted through groove 64 and channel 63, insuring the filling of the spaces with water, which is forced out and leaks away to 11 some extent under the great pressure. By this arrangement I provided a thrust-bearing against the end thrust of the shaft in either direction.

Having thus described my invention, what 11 I claim as new, and desire to secure by Letters Patent, is—

1. In a propeller for navigable vessels, the combination with the main shaft suitably journaled, of a tapering shell secured to the stern of the vessel and rearwardly extending therefrom, said shaft and shell being adapted to be rotated always in the same direction, blades journaled on said shell and outwardly extending therefrom, said blades being concave on their front faces which strike the water, and means to shift the blades on their bearings.

2. In a propeller for navigable vessels, the combination with the main shaft journaled 12

in the vessel and adapted to be turned in one direction, of a tapering shell on the stern of the vessel connected to the shaft, parallel rock-shafts journaled in contact in the shell, 5 a propeller-blade on each rock-shaft, and means to rock the shafts to vary the inclination of, or to reverse the blades.

3. In a propeller for vessels, the combination with a rearwardly-extending tapering shell, means to attach the shell to the vessel and to connect it to turn with the shaft, parallel rock-shafts journaled in contact in the shell, a propeller-blade on each rock-shaft outwardly extending from the shell, said blades being concave on their corresponding faces, lever-arms connected respectively to each rock-shaft, links on the outer ends of the lever-arms, a cross-head connecting the links, a shifting-bar connected to the cross-head, and means to shift the shifting-bar to shift or reverse the blades.

4. In a propeller for navigable vessels, the combination with the main shaft suitably journaled in the vessel and adapted to be rotated always in the same direction, of a rearwardly-extending tapering shell on the stern of the vessel, means to connect the shell to rotate with the vessel and screw-propeller, blades carried on said shell and outwardly extending therefrom, said blades having their greater portion arranged at the rear of their cross-axes, and their front margins rearwardly and outwardly inclined, and being formed with concave faces to strike the water, said concave faces, being curved outwardly toward their rear margins with a gradually-increasing pitch, substantially as described and shown.

described and shown.

5. In a propeller for navigable vessels, the combination with the main shaft journaled in the vessel and adapted to be rotated in one direction, of a tapering shell rearwardly extending from the stern of the vessel, flexible connections between the shell and the shaft, parallel rock-shafts journaled in contact in a chamber in the wider portion of said shell, a screw-propeller blade secured on each rock-shaft and outwardly extending from said shell, said blades being concave on the surface which strikes the water with a gradually-increasing pitch, curved lever-arms connected to the respective rock-shafts, said arms being arranged to extend respectively around the opposite rock-shafts, links pivotally connected to the outer ends of said lever-arms, a cross-head pivotally connected to the rear ends of said links, a shifting-bar connected to said cross-head, and means longitudinally to move the shifting-bar to shift the position of the blades.

6. In a propeller for navigable vessels, the combination with the main shaft journaled in the vessel in ball-bearings and adapted to be rotated in one direction, of a tapering shell rearwardly extending from the stern of

the vessel, parallel rock-shafts journaled in contact in a chamber in the wider portion of said shell, a screw-propeller blade secured on each rock-shaft and outwardly extending from said shell, lever-arms connected to the respective rock-shafts, links pivotally connected to the outer ends of said lever-arms, a cross-head pivotally connected to the rear ends of said links, a shifting-bar connected to said cross-head, operating-levers connected to said cross-head to shift the blades, means to lock the operating-levers in adjusted position, and buffer-springs suitably arranged to engage with said parts and oppose a yielding resistance to the strains on the blades. 70 75 80

7. In a propeller for navigable vessels, the combination with the main shaft journaled in the vessel and adapted to be rotated in one direction, of a tapering shell rearwardly extending from the stern of the vessel, the 85 widest portion of said shell being arranged adjacent to the stern of the vessel, flexible connections between the shell and the shaft, parallel rock-shafts journaled in contact in a chamber in the wider portion of said shell, a 90 screw-propeller blade secured on each rock-shaft and outwardly extending from said shell, said blades being concave on the surface which strikes the water with a gradually-increasing pitch, lever-arms connected to the respective rock-shafts, links pivotally connected to the outer ends of said lever-arms, a cross-head pivotally connected to the rear ends of said links, a shifting-bar connected to the center of said cross-head and rearwardly extending through a bearing in the shell, a connecting-arm suitably journaled and engaging at its lower end with a groove in the rear end of the shifting-bar, and operating-levers connected to said connecting-arm longitudinally to move the shifting-bar to shift the blades, substantially as described and shown. 95 100

8. In a propeller for navigable vessels, the combination with the main shaft journaled in the vessel in ball-bearings and adapted to be rotated in one direction, of a tapering shell rearwardly extending from the stern of the vessel and having a slightly convex surface, the widest portion of said shell being arranged adjacent to the stern of the vessel, of a substantially spherical front portion on the shell fitting within a corresponding socket in the stern of the vessel, a ball fitting a socket in said front portion of the shell and journaled therein, a fork on the end of the shaft embracing said ball, said ball being journaled in said fork, parallel rock-shafts journaled in contact in a chamber in the widest portion of said shell, a screw-propeller blade secured on each rock-shaft and outwardly extending from said shell said blades being concave on the surface which strikes the water with a gradually-increasing pitch, curved lever-arms connected to the respective rock-shafts.

- 4
- said arms being arranged to extend respectively around the opposite rock-shaft, links pivotally connected to the outer ends of said lever-arms, a cross-head pivotally connected to the rear ends of said links, a shifting-bar connected to the center of said cross-head, and means longitudinally to move the shifting-bar to shift the position of the blades, substantially as described and shown.
- 10 9. In a propeller for navigable vessels, the combination with the main shaft journaled in the vessel in ball-bearings and adapted to be rotated in one direction, of a tapering shell rearwardly extending from the stern of the vessel and having a slightly convex surface, the widest portion of said shell being arranged adjacent to the stern of the vessel, of a substantially spherical front portion of the shell fitting within a corresponding socket in the stern of the vessel, a ball fitting a socket in said front portion of the shell and journaled therein, a fork on the end of the shaft embracing said ball, said ball being journaled in said fork, parallel rock-shafts journaled in contact in a chamber in the wider portion of said shell, a screw-propeller blade secured in each rock-shaft and outwardly extending from said shell, said blades being concave on the surface which strikes the water with a gradually-increasing pitch, curved lever-arms connected to the respective rock-shafts, said arms being arranged to extend respectively around the opposite rock-shaft, links pivotally connected to the outer ends of said levers, a cross-head pivotally connected to the rear ends of said links, a shifting-bar connected to the center of said cross-head and rearwardly extending through a bearing in the shell, a curved shoe pivotally secured to the stern of the vessel below the shell and rearwardly and upwardly extending around the shell and provided with a slot fitting a guide-bolt above, means to swing and to slide the shoe slightly longitudinally to adjust said shoe on its bearing, a slotted bracket on said shoe, a connecting-arm journaled on said shoe to fit in the guide-slot of said bracket and engaging at its lower end with a groove in the rear end of the shifting-bar, a forwardly-extending operating-lever pivotally connected to the upper end of said connecting-arm, bearings for said operating-lever, a hand-lever connected to slide said operating-lever forward and back to shift or reverse the blades, buffer-springs arranged between said hand-lever and shoulders on said operating-lever, and a latch on said hand-lever engaging with a suitable rack to lock the parts in adjusted position.
- 15 10. In testimony whereof I affix my signature in presence of two witnesses.
